UNITED STATES PATENT OFFICE

JOHN L. HYLAND, OF NEW YORK, N. Y.

FOLDING DAVIT

Application filed May 6, 1929. Serial No. 360,803.

This invention relates to combined chocks and davits which may be hinged or folded for the storing of lifeboats upside down on the deck of a vessel and a braking device for insuring a safe lowering and launching of lifeboats by one man in about one-tenth the time it now takes. This system of storing also allows about thirty percent more lifeboats to be stored on the ship's deck in the same space that the present equipment takes.

The object of the invention is to simplify and improve the method of launching lifeboats by the provision of folding davits to be placed on the deck of a vessel to receive and support the lifeboats in inverted positions, and to cause the lifeboats to be launched in about one-tenth the length of time it ordinarily requires and in an improved manner. The supporting of the lifeboats in an inverted position on the deck of the vessel greatly lengthens the life of the lifeboats and preserves them to facilitate the launching thereof, and it also preserves the equipment used in lowering the lifeboats and facilitates the launching thereof with less than one-half of the equipment now used, and from either the lifeboat or the ship's deck.

In the accompanying drawings:

Fig. 1 is a top plan view of the invention;
Fig. 2 is a side elevation of the same;
Fig. 3 is a horizontal sectional view through the supporting mechanism for one of the davits;

Fig. 4 is a vertical sectional view through the same;

Fig. 5 is a detail sectional view of one of the brakes;

Fig. 6 is a plan view of a modified arrangement; and
Fig. 7 is a detail.

The deck, or other convenient part of the vessel, upon which the lifeboat is to be supported and secured is designated generally by the numeral 1. Supported by the deck 1 and extending upwardly therefrom in spaced relation, as shown in Fig. 1, are supporting structures 2, which are of convenient framework to support the davits 3, which are supported on the structures 2. The davits 3 have notches 5 at the opposite ends thereof

to receive the sides of the lifeboat 6, as shown in dotted lines in Fig. 2.

The lifeboat is held in position on the davits 3 by means of cables 7, each having one end secured to a pin 8 extending transversely of each of the davits 3, and the opposite end of each cable 7 extends about a sleeve 9 and is coiled thereon, so that when this sleeve is turned it causes a coiling or uncoiling of the cable. The sleeve 9 is mounted and supported on the shaft 10, with which it has a screw-threaded connection so that upon the sleeve 9 being turned it is fed lengthwise of the shaft 10. The shaft 10 is securely fastened or mounted in a convenient part of the lifeboat. The turning of the sleeve is normally retarded by means of a screw 11 which bears thereagainst and may be adjusted by means of a hand-wheel 12. This screw is threaded through a plate 13 mounted in the lifeboat.

The lifeboat 6 is supported in an inverted position on the davits 3, and in order to turn this lifeboat to an upright position, the davits 3 are pivoted at one end, as at 4, to ears 14 extending outwardly from and carried by levers 15, which are of approximately L-shape, having the short-arm thereof pivoted as at 16 in slots 16' in the supporting structure 2, the long arm of the L-shaped levers 15 extending beneath and supporting the davits approximately throughout their lengths, as shown in Fig. 2.

Supported within each of the structures 2 is an angular drum 17 pivoted as at 18 thereto. A cable 19 extends about this angular drum 17, having one end fixed to the drum and extends over a rod 20 and is coiled about a shaft 21. This shaft 21 extends lengthwise between the supporting structures 2 and receives both of the cables 19, the free ends of each of the cables 19 being secured to the shaft 21. A coil spring 22 has one end thereof fixed to the pivot 18, and the other end to the angular drum 17 for normally tending to return this frame to its initial position.

Rollers 23 and 24 are carried by the angular drum 17 and normally bear against the underside of each of the levers 15, so that when the shaft 21 is turned to coil the cable 19 thereon, this causes a tilting of the angular

drum 17 and causes the rollers 23 to be forced upward, turning the levers 15 and davits 3 about the pivot 16, which turns the lifeboat to an upright position beside the deck of the 5 main vessel.

Connected with the inner end of each of the davits 3 is a cable 25, which extends downwardly and is also coiled about the shaft 21 in a direction opposite to that in which 10 the cable 19 is coiled thereon, to be wound or unwound oppositely to the corresponding action of the cable 19. A wheel 26 may be connected with the shaft 21 to turn said shaft and this wheel may be either manually or 15 power actuated.

A braking device, designated generally by the numeral 27, may be applied to the shaft 21 and may be of a construction similar to that shown in Fig. 5, so as to retard the movement 20 of the shaft when the davits 3 have been turned to an extreme position, if this should be necessary or desirable.

In using the invention, the lifeboat 6 will normally be supported in an inverted position 25 on the davits 3, which will be located in the full line position of Fig. 2, and when it is desired to lower the lifeboat, the turning of the shaft 21 will cause an unwinding of the cable 25 and a winding or coiling of 30 the cables 19, which tilts the angular drum 17 about their pivots 18 and the bearing of the rollers 23 against the underside of the levers 15 moves these upward about their pivots 16 to an angular position, causing the 35 pivots 16 to drop downward in the slots 16' so that the weight of the lifeboat will then be sufficient to cause a further movement of this and the davits 3 approximately to a horizontal position, the lifeboat being upright. 40 The lifeboat is held on the davits by means of the cables 7, which are wound onto the sleeve 9.

If the hand-wheel 12 is turned slightly to release the braking action on this sleeve, 45 the weight of the lifeboat on the cables will cause an uncoiling of the cables and a lowering of the lifeboat. The reason for the threaded connection between the sleeve 9 and shaft 10 is to feed the sleeve longitudinally 50 as the cable uncoils, so as to keep the cables in upright positions. In replacing the lifeboat on the davits, this action may be reversed and some convenient means applied to the sleeve 9 to turn the latter.

55 In the form shown in Fig. 6, the levers 15 are pivoted in the slots 16' to the structures 2, each of which is provided with a curved edge 28 (see Fig. 7). The davits 3 are pivoted to the levers 15 as in Figs. 1 to 4.

60 Separate shafts 29 and 30 are journaled in the supporting structures 2, in alignment, and are securely threaded into a sleeve 31, which is tapered toward the shaft 30. The opposite end of this shaft 30 is threaded into 65 a fixed standard 32, so as to move the shaft

longitudinally when turned. The shafts 29 and 30 are provided with holes 33 for the insertion of a pin to turn the same, and a wheel 34 is also provided on the shaft 29 for the same purpose.

70 A locking device 35, of a form similar to that shown in Fig. 5, is mounted to cooperate with the sleeve 31 to limit the rotation thereof.

Ropes 36 each have one end fixed to one of the shafts 29 or 30 and in opposite directions, and extend over pins 37 mounted at the outer ends of the davits 3 and are wound around the opposite ends of a sleeve 38 carried by 75 shafts 39 and 40 and having a threaded connection with the shaft 39, the shafts 39 and 40 being fixed to the lifeboat 6. The sleeve 38 is provided with a tapered portion 41 with which a braking device 42 cooperates to control the lowering of the lifeboat.

80 With this form (Fig. 6) the loosening of the ropes 36 allows the pivot 16 to drop in the slot 16' which will shift the center of gravity sufficiently for the weight of the lifeboat to automatically cause a launching 85 thereof. The brakes 35 or 42 acting on the tapered sleeves 31 and 41 to prevent an unwinding of the cables until released and then only to the extent released, which allows a 90 lowering of the lifeboat either from on deck or within the lifeboat and automatically by the loosening of either of the brakes.

95 I claim:

1. In a device of the character described, 100 the combination of a supporting structure, an approximately L-shaped lever having the short arm thereof pivoted to the supporting structure, a davit pivotally connected with the upper portion of the lever and disposed along the long arm thereof for receiving a life-boat in inverted position, means for securing said life-boat to the davit, and means for turning the lever and davit about their respective pivotal points for turning the life-boat to an upright position.

105 2. In a device of the character described, 110 the combination of a supporting structure, a davit pivotally carried thereby, an angular drum pivotally connected with the supporting structure and in position to cause an upward pivotal movement of the davit, and means for moving the drum.

115 3. In a device of the character described, 120 the combination of a supporting structure, a davit pivotally supported thereon for receiving the life-boat in an inverted position, an angular drum carrying rollers, pivotally disposed beneath the underside of the davit for causing an upward turning movement thereof to turn the life-boat to an upright position, and means for moving the drum.

125 4. In a device of the character described, 130 the combination of a supporting structure, a davit pivotally supported thereon for receiving the life-boat in an inverted position, an

angular drum carrying rollers, and pivotally disposed beneath the underside of the davit for causing an upward turning movement thereof to turn the life-boat to an upright position, a cable coiled about the angular drum, and means for winding said cable to tilt the drum.

5. In a device of the character described, the combination of supporting structures 10 mounted in spaced relation near the side of a boat, davits pivotally mounted on said supporting structures for receiving a life-boat in inverted position, angular drums disposed under and bearing against the davits 15 for causing an upward turning movement thereof to move the lifeboat to an upright position, cables wound about said drums and having the inner ends thereof connected with the drums, a shaft on which said cables are 20 coiled, and additional cables coiled on said shaft in the opposite direction and extending therefrom to the inner ends of the davits.

6. In a device of the character described, the combination of lowering cables for a life-boat, a shaft for receiving the cables and 25 having a tapered portion, means for engaging the tapered portion, and means for causing relative longitudinal movement between the tapered portion and the engaging means, 30 said tapered portion and its engaging means cooperating to limit said longitudinal movement and control the release of the cables.

7. In a device of the character described, the combination of cables attached to a life-boat for lowering the same, a shaft having a 35 tapered portion and receiving the cables, means for causing a longitudinal movement of the shaft upon turning thereof, and means cooperating with the tapered portion 40 for controlling the release of the cables.

8. In life boat launching apparatus, the combination of supporting members having pivoted ends, supporting means for said pivoted ends, said supporting means being 45 constructed and arranged for vertical sliding movement of the pivoted ends, a lever for causing swinging movement of the supporting members on the pivots, and having means for holding the pivoted ends in an elevated 50 position, a swinging movement of the lever in one direction causing a release of the last-mentioned holding means and a swinging of the supporting members on the pivots.

In testimony whereof I affix my signature.
JOHN L. HYLAND.
